ENDLESS, SELF-CLAMPING HANDLED BAND

James H. Reichart, Muncie, Ind.

Application November 15, 1943, Serial No. 510,257

17 Claims. (Cl. 294—27)

This invention relates to a handled band for article attachment.

This application is an improvement over application, Serial No. 498,220, filed August 11, 1943, and entitled Glass vessel band and handle structure, wherein the endless band includes an open buckle, etc., which when collapsed toward the article rigidly clamps the band thereon, and when extended therefrom elongates the band for detaching therefrom.

The chief object of the present invention is to provide a handle connection to the band whereby mounting of the latter upon the article rigidly clamps the handle to its connecting means, in turn connected to the band.

The chief feature of the present invention resides in the "crossed draw string" effect of the handle socket forming connecting means.

Other objects and features of the invention will be set forth more fully hereinafter.

The full nature of the invention will be understood from the accompanying drawing and the following description and claims:

In the drawing

Fig. 1 is a top plan view of a handled band embodying the invention and as applied to a peripherally grooved article, the latter being shown in horizontal section at the groove portion thereof.

Fig. 2 is a vertical central section of the connecting means, the immediately contiguous portion of the article and a side elevation of a pistol grip handle horizontally receivable by the connecting means.

Fig. 3 is a perspective view of the major portions of the socket and connecting means in slightly separated relation.

Fig. 4 is a view similar to Fig. 1 and of a modified form of the invention.

Fig. 5 is a perspective view of the connecting means in handle clamping position, the handle being of the form shown in Fig. 4.

Fig. 6 is a view similar to Fig. 5 and of a still further modified form of the invention.

In Figs. 1 and 2 of the drawing 10 indicates a glass or like article (vessel) having a peripheral groove 11 therein on its exterior surface. If the vessel be of pot or pitcher type, it may have the mouth 12.

A metal band 13 is of a width so that it may seat in groove 11. Such band includes an open buckle or loop 14 pivotally connected to curled ends 15 and 16 of the band. The band adjacent end 15 is arched as at 17 and includes a finger piece 18.

When the loop is caused to move away from the article, the band is elongated and consequently may be readily detached therefrom or applied thereto. When the loop is forced, over center as it were, and toward the article, the band is collapsed or tautened upon the vessel all as set forth more fully in the aforesaid application specifically made a part hereof.

A groove seatable strap member 19 is rigidly secured as at 20 to band 13 adjacent, but not necessarily so, to the buckle structure. A similar but reversely directed strap 21 is similarly secured to band 13 as at 22. Herein such connections are rivets. The adjacent ends of these two straps 15 lap each other as illustrated most clearly in Fig. 3.

Strap 19 includes a wide portion 23 that is wider than groove 11 so that it may bear on the article above and below the groove. Extending radially outward, as it were, from the wide portion 24 is side portion 25. The side portion includes upper and lower flanges 26 and 27 and these at the outer ends are extended as ears 28 and 29 and same are apertured as 30 and 31 respectively.

25 The junction 24 between face portion 23 and side 25 is slotted as at 32 to pass strap 21 as shown. Strap 21 includes a wide portion 33 and same is offset inwardly as at 34 and then continued as at 35 and from the end thereof as at 36 there extends, radially outward as it were, the side portion 37 having upper and lower flanges 38 and 39 with ear extensions 40 and 41 apertured at 42 and 43 respectively and directed toward the other flanges and ears.

35 The wide portion 33—35 is slotted at the offset portion 34 as at 44 and the junction 36 is also slotted at 45. These slots 44 and 45 are aligned and slidably receive strap 19 aforesaid. Rivets 46 and 47 pivotally, see Fig. 2, connect ears 28—40 and 29—41. The several ears and flanges form a socket adapted to radially receive anchor portion 48 of handle 49.

Herein each side face 25—37 is indented as at 50 and anchor portion 48 is similarly indented 45 at 48a. Note that when the band is not collapsed indentations 50 are spaced apart, a distance greater than the width of anchor portion 48. When so positioned, the width of the throat of the socket at the ears is just sufficient to pass anchor portion 48. To facilitate rivet clearance the portion 48 may be cut away as at 51, see Fig. 2.

50 It will be noted that the depth of portions 23 and 35 is greater than the socket depth. This 55 permits the metal between these portions and

the sides and flanges to be drawn or folded to reenforce the junction therebetween.

Whenever the band is tensioned by collapse thereof as previously explained, there is exerted on straps 19 and 21 opposing pulls which cause the two spaced sides to draw together and rigidly clamp therebetween the anchor portion 48 of handle 49. These straps or tongues also, by way of a guy wire effect as it were, draw the article bearing portions 23 and 35 into engagement with the article 10 immediately above and below the groove 11. These straps or tongues immediately adjacent these portions are slightly spaced from the article, and by reason thereof, the guy wire effect is retained and maintained so long as the band is mounted on the article.

Note, see Fig. 3, that one socket forming and article bearing portion is provided with parallel dual slots while the other includes a singular parallel slot for sliding accommodation of the two straps, which are accordingly aligned thereby, and thus any tendency for askew positioning is eliminated which might occur since the slots are slightly spaced from the article engaging facially contacting surfaces. The flanges on the sides form upper and lower handle anchor portion seats.

In view of the fact that the buckle including structure, see Fig. 1, has eyes 15 and 16, it is obvious that, if desired, these may be last fabricated and connected together as shown whenever it is desired to have the straps constitute integral portions of the band 13.

The advantage of having the slots positioned as illustrated instead of spaced outwardly from portions 23 and 35 is that the tension or stress is peripherally applied, thereby making a more rigid assembly when mounted, etc.

Means for pivotal connection of the ears other than rivets 46 and 47 may be employed whenever desired. One of such forms is an extruded rivet formed from the inner ear and extending through the aperture in the outer ear, the two pair of ears being interfitting or nesting as shown in Fig. 2. This hinging at the entrance end of the resulting socket results in the least constriction thereof when the walls are tilted for anchor portion insertion in the socket. While the socket and anchor portion are herein disclosed as generally rectangular in cross-sectional outline, same need not necessarily be of that character, but other polygonal outlines, etc., may be utilized to prevent anchor portion rotation.

The spring or hinge-like connection of the socket sides together with the included embossments 50 fitting into complementary recesses 48a in the anchor portion, upon collapse of the sides to anchor portion engagement, clampingly retain said handle in and to the socket and the interlock prevent axial separation between the socket and anchor portion. Such locking is as effective as a wedge lock between handle and socket, but use of the wedge would result in extreme sloppiness between socket throat and the wedge neck. This is eliminated since the sides herein facially bear on the sides of the anchor portion when the band is article mounted.

Having thus described in detail one embodiment of the invention together with its attendant advantages of construction and use, reference will now be had to Figs. 4 and 5 wherein a second form of the invention is illustrated. This form is distinguished from the previous one by the socket being directed at right angles to the other socket (which was radially directed) and

by said socket being of integral construction instead of comprised of two non-integral side portions, etc.

In said last mentioned figures the straps are designated by 59 and 61 and the former includes two longitudinally aligned apertures 58 and the latter similarly aligned apertures 57 whereby said straps are connected to band 56 identical or similar to band 13, etc. Strap 59 is enlarged vertically as at 63 while strap 61 is similarly enlarged as at 65. Each enlargement is integral with a socket forming side portion 64 at 62 and these extend radially outward from bearing portions 63 and 65 and their outer ends are joined by the curved portion 66.

Side portion 64 connected to bearing portion 63 is slotted at 67 to pass strap 61 and this slot is coincident with junction 62 or spaced radially from portion 63. Bearing portion 65 is slotted at 68 and 70. The resulting portion 69 between slot 68 and slot 70 at the other junction 62 is slightly offset so it can nest in the article groove.

Tension pulls on the straps 59 and 61 in opposite directions naturally draw the sides 64 of the socket together, the curved portion 66 permitting same. Handle 71 having anchor portion 72 is vertically seated in the socket and then the band is applied to the article and tautened thereon as illustrated in Fig. 1 and as previously described.

To prevent pull-out of the handle, each side portion 64 is herein indented or embossed as at 73 which embossments are positioned transverse to the position of embossments 50 in Fig. 1. In each case the embossments are at right angles to the longitudinal direction of the socket. Herein anchor portion 72 in its two opposite faces includes complementary recesses 74 for embossment seating.

This structure as stated has the same operation application, uses and advantages of that illustrated in Figs. 1 to 3 and previously described.

Reference will now be had to Fig. 6 wherein the simplest form of the invention is illustrated. This form in general is of Figs. 4 and 5 type in that handle 80 has a vertical anchor portion 81. Two upper grooves 82 are sufficient. If desired, two lower grooves, as shown, may be provided.

Herein 83 and 84 indicate adjacent portions of a band which is like band 13 shown in Fig. 1 with its buckle structure, etc. End 83 has eye 85. End 84 is reduced at 86 and terminates in eye 87. Pintle portion 88 is in eye 85 and pintle portion 89 is in eye 87. Parallel rod portions 90 extend from opposite ends of portion 88 while oppositely directed parallel rod portions 91 extend from opposite ends of portion 89. When the band is tautened all four parallel portions lie parallel to each other and in substantially a common plane and engage the article above and below the groove, or the upper and lower-most only so engage while the intermediate portions may nest in the groove.

Extending radially from the other ends of portions 90 are the side members 92 and similarly from the other ends of portions 91 there are the side members 93. The remote ends of a member 93 and a member 92 are connected by mid-portion 94. Herein portions 94 are transverse to portions 92 and 93 and each of the latter includes a slight offset near portion 94. However, if desired, such offsetting may be eliminated. Likewise portions 94 may be arched, similar to portion 66 in Figs. 4 and 5.

When the socket receives the handle anchor

portion, the side members seat in the anchor grooves aforesaid and when the band is tautened, the side members clamp the anchor portion therebetween.

In all forms of the invention opposite pulls on the straps or the like of band structure tightens the socket upon the sides of the handle anchor portion for retention thereof, pull-out being prevented by complementary interlocking connections therebetween, the said opposite pulls being incident to band tautening upon the article.

While the invention has been illustrated and described in great detail in the drawing and foregoing description, the same is to be considered as illustrative and not restrictive in character.

The several modifications described herein as well as others which will readily suggest themselves to persons skilled in this art, all are considered to be within the broad scope of the invention, reference being had to the appended claims.

The invention claimed is:

1. In combination an endless band contractible and extensible for article envelopment and mounting thereon and demounting therefrom, a handle having an anchor portion, and a socket for anchor portion reception and retention comprising a pair of sides connected to and included in the band in criss-cross relation whereby band contraction in article mounting causes side clamping of the anchor portion.

2. Structure as defined by claim 1 wherein the socket is of tubular type with the tubularity substantially radial to socket connecting portion of the band.

3. Structure as defined by claim 1 wherein the socket is of tubular type with the tubularity substantially parallel to the axis of the enveloping band.

4. Structure as defined by claim 1 wherein the socket is of tubular type with the tubularity substantially parallel to the axis of the enveloping band, the sides of the socket being connected together by a curved portion.

5. Structure as defined by claim 1 wherein the socket is of tubular type with the tubularity substantially parallel to the axis of the enveloping band, the sides of socket comprising spaced pairs of opposed portions, each pair of opposed portions being connected together by an intermediate portion.

6. Structure as defined by claim 1 wherein the socket and anchor portion have interlocking complementary formations resisting handle-socket separation in a direction opposite to the anchor portion mounting direction.

7. Structure as defined by claim 1 wherein the sides, remote from the band connection thereto have a hinge connection therebetween.

8. Structure as defined by claim 1 wherein the sides, remote from the band connection thereto have a hinge connection therebetween, said last mentioned connection being integral with the sides.

9. Structure as defined by claim 1 wherein the sides, remote from the band connection thereto have a hinge connection therebetween, said last mentioned connection including pivot supporting ears and pivot means.

10. In combination a handle clamping socket

and a pair of band portions connected thereto and subject to tensile stress in opposite directions, said socket comprising a pair of superposed polygonal outlined arranged wire portions, and

5 two pivot providing portions connecting said wire portions at opposite ends, each band portion terminating in a pivot seating eye formation.

11. In combination a handle clamping socket and a pair of band portions connected thereto

10 and subject to tensile stress in opposite directions, said socket comprising a pair of superposed polygonal outlined arranged wire portions, and two pivot providing portions connecting said wire portions at opposite ends, each band portion

15 terminating in a pivot seating eye formation, one pivot portion being of lesser length than the other.

12. In combination a handle clamping socket including a pair of adjacent, article engageable

20 bearing portions, a side portion connected to each, the side portions being connected together, the socket including three slots, one in juxtaposition to the side-bearing portions junction and an intermediate slots in one of the bearing portions,

25 and a pair of band connected means, each rigid with a bearing portion and slidable in a slot whereby socket clamping occurs when said means are subjected to tensile stress in opposite directions.

30 13. Structure as defined by claim 12 wherein each side portion includes upper and lower edge inwardly directed flanges, said side portions remote from said means having spaced pivotal connections to provide a handle receiving socket

35 throat.

14. In combination a handle clamping socket including a pair of adjacent, article engageable

bearing portions, a side portion connected to each, the side portions being connected together, the socket including three slots, one in juxtaposition to the side-bearing portions junction and an intermediate slot in one of the bearing portions,

40 and a pair of band connected means, each rigid with a bearing portion and slidable in a slot whereby socket clamping occurs when said means are subjected to tensile stress in opposite directions, each bearing portion being of greater length than the width of the band connected means.

45 15. Structure as defined by claim 14 wherein each side portion includes upper and lower edge inwardly directed flanges, said side portions remote from said means having spaced pivotal connections to provide a handle receiving socket

throat.

50 16. Structure as defined by claim 14 wherein each side portion includes upper and lower edge inwardly directed flanges, said side portions remote from said means having spaced pivotal connections to provide a handle receiving socket

55 throat, the distance between flanges of the same side being less than the length of said bearing portions.

17. In combination an article mountable enveloping band subject to tension when mounted,

60 and a handle receiving socket having side portions cross connected to the band and subject to the tension thereof for handle clamping purposes.

JAMES H. REICHART.
